UNITED STATES PATENT OFFICE.

FERDINAND P. KAISER, OF ST. LOUIS, MISSOURI.

EAR-MUFFLE.

SPECIFICATION forming part of Letters Patent No. 437,602, dated September 30, 1890.

Application filed March 17, 1890. Serial No. 344,161. (No model.)

To all whom it may concern:

Be it known that I, FERDINAND P. KAISER, of the city of St. Louis, in the State of Missouri, have invented a certain new and useful Improvement in Ear-Muffles, of which the following is a full, clear, and exact description, reference being had to the accompanying drawings, forming part of this specification.

10 The object of this instrument is to prevent sound entering the ear. It is specially intended for use by a person receiving a telephone-message, being placed upon one ear while the telephone-receiver is applied to the other. It is found that when one ear is muffled the efficiency of the other ear is increased, as the nervous energy is concentrated upon it. The device is supported entirely by the ear.

20 Figure I is an inside view of the device. Fig. II is a vertical section showing the device applied to the left ear, which is shown in front view.

25 1 is a sheet of rubber, celluloid, or any other suitable material. This sheet is molded to fit and cover either the right or left ear, as the case may be.

30 2 is a flange, which extends around the top and back of the sheet 1, and which extends around the rim 3 of the ear at the top and rear and engages on the said rim, so as to support the instrument upon the ear. The part 4 of the edge between the ends of the flange 2 is curved inward, so as to lie against the cheek to check the entrance of sound to the orifice of the ear.

35 The orifice of the ear is closed by a plug 5,

which extends inward from the part or sheet 1. This plug is intended to be made of rubber or other suitable flexible or inflexible material and of such form as to substantially close the orifice of the ear. 40

In some cases I attach to the part 1 a disk, fringe, or border 6, extending from the part 1 all around and curved inward, so that its 45 edge 7 is in contact with the side of the head, as seen in Fig. II. In most cases the border 6 would not be required; but in cases where there is much noise or the listener is very sensitive this border will be found advan- 50 tageous.

I claim herein as new and of my invention—

1. The combination, in an ear-muffle, of the sheet 1, covering the ear, and the plug 5, entering the orifice of the ear, substantially as 55 set forth.

2. The sheet 1, covering the ear and having a flange 2 engaging the rim of the ear, in combination with the plug 5, adapted to fit the orifice of the ear. 60

3. The combination of the sheet 1, adapted to the outer side of the ear, the flange 2, adapted to engage the rim of the ear, and the border 6, extending from the sheet on all sides, substantially as and for the purpose 65 set forth.

4. The combination, in an ear-muffle, of the sheet 1, carrying a plug 5 and having a flange 2 and the border 6, all substantially as and for the purpose set forth.

FERDINAND P. KAISER.

In presence of—

THOS. KNIGHT,

E. S. KNIGHT.
